UNITED STATES PATENT OFFICE.

WILLIAM B. TIMMONS, OF TRENTON, MISSOURI.

GROCER'S BIN.

1,150,317.

Specification of Letters Patent. Patented Aug. 17, 1915.

Application filed July 8, 1914. Serial No. 849,779.

To all whom it may concern:

Be it known that I, WILLIAM B. TIMMONS, a citizen of the United States, residing at Trenton, in the county of Grundy and State of Missouri, have invented certain new and useful Improvements in Grocers' Bins, of which the following is a specification, reference being had to the accompanying drawings.

10 This invention relates to an improved grocer's bin for containing potatoes, apples, and like commodities, and has for its primary object to produce a device of this character which is strong and durable in its construction, highly serviceable and convenient in practical use and may be produced at small manufacturing cost.

15 The invention has for another and more specific object to provide a bin of the above character including a base having a wide open end and provided with means for directing the contents of the bin toward the open end thereof and a hopper or container removably mounted upon the rear end of said bin.

20 With the above and other objects in view, the invention consists in novel features of construction, combination and arrangement of parts as will be hereinafter referred to 25 and more particularly pointed out in the specification and claims.

25 For a full understanding of the invention, reference is to be had to the following description and accompanying drawing, in which—

30 Figure 1 is a side elevation of a grocer's bin constructed in accordance with the preferred embodiment of my invention; Fig. 2 is a front elevation thereof; Fig. 3 is a vertical section; and Fig. 4 is a section taken 35 on the line 4—4 of Fig. 3.

35 Referring in detail to the drawing, 5 designates the opposite side walls of the base portion of my improved bin. This base 40 structure is preferably bottomless and is adapted to be arranged upon the floor or other suitable support which will constitute the bottom of the bin. These side walls are connected at one of their ends by an up- 45 standing rear wall 7 and at their forward ends by a forwardly and upwardly inclined front wall 8. This latter wall is preferably 50 spaced slightly from the forward edges of the side walls 5. Metal angle bars indicated 55 at 9 are secured to the forwardly projecting ends of the side walls, the inwardly extend-

ing flanges 9' thereof acting to support and brace the inclined front wall 8. The upper edges of the side walls 5 at their forward ends are downwardly inclined as shown at 50 10 and the upper edge of the front wall 8 is disposed below the plane of the upper rear edges of the side walls 5 and the upper edge of the rear wall 7. In the rear end of this base portion of the bin, an obliquely inclined directing board 11 is arranged, said board being disposed at a reverse inclination to the front wall 8 and adapted to direct the contents of the bin into the forward end portion of the base from which they 55 may be easily removed.

12 indicates the hopper or container which is mounted upon the rear end of the base portion of the bin. This container is constructed of the solid side and rear walls 13 and 14 respectively, and is provided with a front wall consisting of a plurality of spaced vertical bars or slats 15. To the upper and lower ends of these bars, as well as the rear and side walls of the container, 60 the cleats 16 are secured and at the corners of the container, the angular metal reinforcing straps 17 are securely bolted, the bolts indicated at 18 extending through the walls of the container. The rear wall 14 65 of the hopper or container projects below the front and side walls thereof as shown at 19. This downwardly projecting portion of the rear wall is adapted for engagement against the inner face of the rear wall 7 of 70 the base and upon the upper edge of the inclined directing board 11. The cleats 16 secured to the lower ends of the container walls rest upon the upper edges of the base walls.

75 Upon the vertical slats constituting the front wall of the container and immediately above the cleats 16 a suitable shelf 20 is hinged at one of its ends as shown at 21. The other end of this shelf is provided in its 80 bottom face with a notch or recess 22 to receive the front end of a supporting bar 23, which is hinged at its other end as at 24 upon the lower edge of the cleat 16. When the shelf 20 is disposed in its horizontal position as shown in Fig. 3 of the drawing, 85 the inner end thereof is supported upon the upper edge of the cleat 16, while the outer end is supported by means of the bar 23.

90 Having above described the several structural features of my improved grocer's bin, 95 its several advantages in practical use will

be manifest. The hopper or container 12 is mounted or disposed upon the rear end of the article receiving base, but is not secured thereto in any manner. The contents of the 5 container and the downwardly projecting end 19 of the rear wall thereof serve to prevent longitudinal shifting movement of the container with respect to the base. The container 12 may, however, be readily removed 10 when desired in order to admit of the easy and thorough cleaning of the base portion of the bin by simply drawing or sliding the container forwardly upon the rear upper edge portions of the side walls 5. The po- 15 tatoes or other commodities contained in the bin or hopper 12 are directed forwardly to the front open end of the receiving base by the inclined wall 11. The measure or other receptacle to receive the potatoes may be 20 conveniently placed upon the shelf 20, while the forwardly projecting wide open end of the base permits of easy access to the contents thereof.

It will thus be seen that I have provided a 25 very desirable bin construction, and one which is of great service and convenience in practical use.

It may be ascertained when the hopper or container 12 needs replenishing, as the contents thereof are visible through the spaces between the front vertical slats or bars 15.

The container may, of course, be constructed in various sizes in accordance with the capacity desired, and owing to the sec- 35 tional construction of the bin, the same may be compactly stored when not in use.

It will further be appreciated that in view of the very simple construction of my invention, the same is very strong and durable 40 and may be produced at comparatively small manufacturing cost.

While I have above described the preferred form, construction, and arrangement of the several elements employed, it will be 45 understood that the device is, nevertheless, susceptible of considerable modification therein, and I therefore reserve the privilege of resorting to all such legitimate changes as may be fairly embodied within 50 the spirit and scope of the invention as claimed.

What is claimed is:

1. A bin of the character described in- 45 cluding a base structure having vertical side

walls, a rear vertical wall, and a forwardly 55 and upwardly inclined front wall secured between said side walls, an obliquely in- 60 clined wall arranged between the rear ends of the side walls to direct the contents of said base structure forwardly, and a con- 65 tainer removably mounted upon the rear upper edges of the side walls and having an extension formed upon one of its walls de- 70 pending below the lower edges of the re- 75 maining walls of said container and resting 80 upon the upper edge of said inclined direct- 85 ing wall.

2. A bin of the character described in- 70 cluding a base structure having vertical side 75 walls, a rear vertical wall, and a front wall 80 having its upper edge below the upper edge 85 of said rear wall, a container removably 90 mounted upon the upper edges of said side 95 and rear walls and having unobstructed lon- 100 gitudinal sliding movement with respect to the base structure in one direction, and a supplementary support fixed in the rear end of the base structure to sustain a portion of the weight of said container.

3. A bin of the character described in- 80 cluding a base structure having vertical side 85 walls, a rear vertical wall, and a forwardly 90 and upwardly inclined front wall having its 95 upper edge disposed below the upper edge 100 of said rear vertical wall, an obliquely in- clined directing wall secured between the side walls of said base structure and engaged at its upper edge with said rear wall at a point below the upper edge of the latter, and a container removably mounted upon the upper edges of said side and rear walls of the base structure, the rear wall of said container having a depending portion to extend downwardly upon the inner face of the rear wall of said base and rest upon the upper edge of the inclined directing wall, the for- 105 ward end of the base structure being open at its top whereby said container may be moved longitudinally upon the side walls of the base in a forward direction and removed 110 therefrom.

In testimony whereof I hereunto affix my signature in the presence of two witnesses.

WILLIAM B. TIMMONS.
